(57) **CLAIM**

The ornamental design for a LED chip, as shown and described.

DESCRIPTION

FIG. 1 is a top perspective view of an LED chip showing our design;

FIG. 2 is a top view thereof;

FIG. 3 is a first side view thereof;

FIG. 4 is a bottom view thereof;

FIG. 5 is a different side view thereof;

FIG. 6 is an end view thereof;

FIG. 7 is an opposing end view thereof;

FIG. 8 is a top perspective view of the LED chip of FIG. 1 with the top surface removed;

FIG. 9 is a top view thereof;

FIG. 10 is a first side view thereof;

FIG. 11 is a bottom view thereof;

FIG. 12 is a different side view thereof;

FIG. 13 is an end view thereof; and,

FIG. 14 is an opposing end view thereof.

The broken lines define portions of the LED chip that form no part of the claimed design.

1 Claim, 4 Drawing Sheets
